UNITED STATES PATENT OFFICE

126,564

DESIGN FOR A BICYCLE BASKET

Arthur G. Andrews, Rockford, Ill., assignor to The Washburn Company, Worcester, Mass., a corporation of Massachusetts

Application January 17, 1941, Serial No. 98,163

Term of patent 7 years

To all whom it may concern:

Be it known that I, Arthur G. Andrews, a citizen of the United States, residing at Rockford, in the county of Winnebago and State of Illinois, have invented a new, original, and ornamental Design for a Bicycle Basket, of which the following is a specification, reference being had to the accompanying drawing, forming part thereof.

In the drawing:

Fig. 1 is a top view of a bicycle basket embodying the design of my invention;

Fig. 2 is a front view, and

Fig. 3 is a side view.

I claim:

The ornamental design for a bicycle basket, substantially as shown.

ARTHUR G. ANDREWS.
